UNITED STATES PATENT OFFICE.

FITZHUGH L. OVERTON, OF SHREVEPORT, LOUISIANA.

DESIGN FOR A SIGN-DISPLAY BOARD.

Application filed January 7, 1924. Serial No. 8,256. Term of patent 14 years.

To all whom it may concern:

Be it known that I, FITZHUGH L. OVERTON, a citizen of the United States, residing at Shreveport, in the parish of Caddo and State of Louisiana, have invented a new, original, and ornamental Design for a Sign-Display Board, of which the following is the specification, reference being had to the ac-

companying drawing, forming a part thereof.

The figure is a front elevation of a sign display board, showing my new design.

I claim:

The ornamental design for a sign display board as shown.

FITZHUGH L. OVERTON.
